UNITED STATES PATENT OFFICE

2,219,643

CLOSET SEAT

George J. Zaio, Iron Mountain, Mich.

Application July 17, 1939, Serial No. 285,669

5 Claims. (Cl. 4—235)

This invention relates to an improved closet seat and is an improvement on the structure disclosed in my Patent No. 2,155,577, dated April 25, 1939.

5 One object of the invention is to provide a closet seat embodying an auxiliary seat for infants which, when not in use, is contained entirely within the confines of the cover.

Another object of the invention is to provide, 10 in a closet seat, an auxiliary seat which may be quickly swung from inoperative position within the cover, to operative position extending at substantially right angles to the cover.

A further object of the invention is to provide, 15 in a closet seat, an auxiliary seat having a back and side arms, the back cooperating with the auxiliary seat member employed for providing a smooth unobstructed inner surface for the cover.

Another object of the invention is to provide a 20 closet seat which may be quickly installed by merely removing the conventional cover and substituting the cover of my invention, which cover has the auxiliary seat mounted therein.

And as a still further object, the invention seeks 25 to provide a closet seat wherein the cover is formed with means engageable with the auxiliary seat member for retaining the auxiliary seat against accidental displacement from the cover when said auxiliary seat is not in use.

30 Other and incidental objects of the invention will become apparent during the course of the following description.

In the accompanying drawings forming a part 35 of this application:

Figure 1 is a longitudinal sectional view of my improved closet seat, said seat being shown in open position with the auxiliary seat extended for use.

Figure 2 is a longitudinal sectional view of my 40 improved closet seat showing the cover in lowered position and the auxiliary seat completely enclosed within said cover.

Figure 3 is a longitudinal sectional view on the line 3—3 of Figure 1.

45 Figure 4 is a vertical sectional view taken transversely of the closet seat in operative position.

Referring now more particularly to the accompanying drawings, wherein like numerals of reference will be seen to designate like parts throughout the several views, the numeral 1 indicates a water closet which may be of any approved construction. The closet 1 is provided 50 with an adult seat member 2 which is hingedly

connected to the closet 1 by means of hinge members 3 and 4 and a hinge pin 5.

My improved closet seat includes a cover shown generally at 6. The cover is of substantially oval shape and may be formed of any material commonly used for the purpose. As best seen in Figures 1 and 4 of the drawings, the cover 6 is recessed throughout the major portion of its interior to define receptacles 7 and 8 and a relatively thin wall 9. As best seen in Figure 1, the receptacle 7 is relatively large with respect to the receptacle 8, so that a shoulder 10, between said receptacles, is defined, said shoulder extending throughout the major portion of the distance of the circumference of the cover. The cover is 10 formed with a thickened upper portion 11 and said portion 11 is provided medially of its width with a latch 12 which has a latch member 13 extending normally into the receptacle 7. The cover is provided with an open lower end portion 14, the purpose of which is to permit the auxiliary seat member, presently to be described, to be properly connected with said cover.

The auxiliary seat member employed is indicated in general at 15. Said auxiliary seat member is of a size to conveniently receive in sitting position, a child too small to make use of the conventional seat member 2. The auxiliary seat member 15 comprises a flat board of a contour quite similar to that of the seat member 2. Said seat member 15, however, is of such shape that it will snugly but removably fit within the receptacle 7. As best seen in Figure 2, the forward edge portion of the auxiliary seat member 15 is formed with a latch receiving socket 16 which 25 removably receives the latch member 13 when the seat is in the position shown in Figure 2. With further reference to Figure 2, it will be seen that the seat member 15, when in inoperative position, lies with its inner free edge portion abutting the shoulder 10 between the receptacles 7 and 8, said shoulder preventing too great inward movement of the auxiliary seat member. The outer surface of the auxiliary seat member will lie in the same plane with the rim of the cover 30 8 so that an unobstructed inner surface for the cover and auxiliary seat member, when in inoperative position, will be assured.

Hinges 17 and 18 provide a swinging connection between the cover 6 and the auxiliary seat 50 member 15. In order to allow convenient extension of the auxiliary seat member, there is provided a knob 19 which is secured to the outer surface of the auxiliary seat member near its upper extremity. If desired, the knob 19 may be 55

dispensed with and the seat member recessed to define a finger hold. In this manner there will be no projections extending from the otherwise unobstructed surface of my improved closet seat.

- 5 In order to connect my improved closet seat to the hinge pin 5 and thus place it in operative connection with the member 2, hinge members 20 are employed, which hinge members are secured to the lower outer surface of the board 15. It 10 will be understood that the hinge members 20 serve the purpose of connecting the entire device in operative position with the member 2. This is to be particularly noted for the reason that, when installing my improved closet seat, it is only necessary to remove the conventional closet seat cover by disengaging said cover and its hinge members from the hinge pin 5 and substituting the cover 6 with its auxiliary seat member 15. If desired, the entire conventional toilet seat may 15 be removed and my improved structure substituted, in which case the member 2 will be included with the cover 6. This procedure may be found preferable for the reason that proper matching of the cover 6 and seat member 2 will thus be assured.

In order to support a child sitting upon the auxiliary seat member 15, I provide a back 21 which is of oval shape and has a concave edge 22. The back 21 is secured to the auxiliary seat member 15 by means of a hinge 23, and is, as best seen in Figure 2, adapted, when in inoperative position, to rest within the opening 24 of the auxiliary seat member 15. The back serves the two-fold purpose of providing a supporting back, as heretofore set forth and, also, said back 21 serves to define a closure for the opening 24 so that an unobstructed inner surface for the closet seat will be assured.

An arm carrying plate 25 of U-shape configuration in top plan, is hingedly connected to the inner surface of the wall 9 of the cover 6. The plate 25 has arms 26 and 27 which have curved outer edges 28 and straight inner edges 29. The arms 26 and 27 are adapted, as best seen in Figure 3, to straddle the back 21. A hinge 30 connects the back 21 with the bight portion 31 of the plate 25. Extending between the corresponding outer end portions of the arms 26 and 27 is a flexible restraining strap 32 which serves the purpose of retaining a child in position on the auxiliary seat.

The cover and auxiliary seat are prevented from too great relative swinging movement by pivoted links 33 and 34 which are carried on brackets 35 and 36. Swinging of the auxiliary seat member 15 toward the cover 6 will effect swinging of the back 21 and plate 25 with respect to each other so that, in closed position, the plate 25 will, as best seen in Figure 2, be contained in the receptacle 8. When the auxiliary seat member 15 is swung away from the cover 6, the plate 25 will be swung from the receptacle 8 and the back 21 and said plate will assume the position shown in Figure 1 of the drawings.

65 It is believed that further description of the invention is unnecessary.

Having thus described the invention, what I claim is:

1. In a closet seat, an adult seat member, an auxiliary seat member hinged thereto and having an opening, closure means for the auxiliary seat member and being shiftable to close the opening, a cover hingedly connected to the auxiliary seat member and having a receptacle for receiving the auxiliary seat member to lie flush therein and

thus define an unobstructed inner surface for the cover and auxiliary seat, and means operatively connecting the closure means with the auxiliary seat member and the cover, said closure means being movable from the opening upon movement of the cover for defining a back for the auxiliary seat member.

2. In a closet seat, in combination with a water closet having an adult seat member, and means hingedly connecting the adult seat member to the water closet, an auxiliary seat member having an opening, means hingedly connecting the auxiliary seat member to the first mentioned means whereby said auxiliary seat member may swing with respect to the adult seat member, a cover having a hollow interior defining a pair of receptacles, one of said receptacles being relatively large and the other relatively small for defining a shoulder, means hingedly connecting the cover with the auxiliary seat member, said auxiliary seat member being shiftable to lie in the larger of the receptacles adjacent the shoulder for defining an unobstructed inner surface for the cover and auxiliary seat member in closed position, and a back for the auxiliary seat member, said back being shiftable from a position closing the opening in the auxiliary seat member in closed position to a supporting position upon movement of the auxiliary seat member with respect to the cover.

3. In a closet seat, a cover having a hollow interior defining a relatively thin wall, a relatively large receptacle and a relatively small receptacle, a shoulder being defined between the receptacles, an auxiliary seat member having an opening, means connecting the auxiliary seat member and cover to a water closet, an arm carrying plate carried by the cover, means hingedly connecting the arm carrying plate to the cover, a back for the auxiliary seat member, means hingedly connecting the back to the auxiliary seat member, means hingedly connecting the back to the arm carrying plate, said plate having arms straddling said back, and links connected between the cover and auxiliary seat member, said auxiliary seat member being adapted to swing to closed position in the larger of the receptacles, said arm carrying plate lying in the smaller of the receptacles and said back lying in the opening in the auxiliary seat member whereby an unobstructed inner surface will be provided for the cover and said member in closed position, relative swinging of the cover with respect to the seat member effecting shifting of the back and arm carrying plate to operative position.

4. In a closet seat, a cover having a pair of receptacles, an arm carrying plate adapted to lie in one of said receptacles in closed position and to project from the cover in operative position, an auxiliary seat member, means swingingly connecting the auxiliary seat member with the cover whereby said cover may lie in the other of said receptacles in inoperative position and cooperate with the rim of the cover for defining an unobstructed inner surface for the cover and auxiliary seat member, a back for the auxiliary seat member, and means swingingly connecting the back with the arm carrying plate and the auxiliary seat member, said back being adapted to lie in the opening of the auxiliary seat member and cooperate with the cover for defining a smooth unobstructed inner surface for the cover and seat member in closed position.

5. In a closet seat, a toilet seat member, an auxiliary seat member hinged thereto and having

an opening, a back for the auxiliary seat member, means swingingly connecting the back with the auxiliary seat member whereby said back may be moved to inoperative position within the opening in said auxiliary seat member, arms, a cover hingedly connected with the auxiliary seat member, and means operatively connected between

the arms and the cover and being shiftable upon raising of the cover for raising the back to operative position with respect to the auxiliary seat member, said last mentioned means defining arm rests.

5

GEORGE J. ZAIO.
